LOCKING SLIDER FOR SLIDE FASTENERS

Bernard S. Franklin, New York, N. Y., assignor to
Conmar Products Corporation, Bayonne, N. J.,
a corporation of New Jersey

Application February 2, 1940, Serial No. 316,881

17 Claims. (Cl. 24—205.5)

This invention relates to slide fasteners, and more particularly to locking sliders for the same.

The primary object of my invention is to generally improve locking sliders for slide fasteners, and more especially sliders of the automatically locking type.

Another object is to provide a lock action of such nature that it may be applied to slide fasteners intended to be used in inverted position or in upright position, although the specific construction of the slider particularly centering about the pivoting of the pull thereon, may differ for these two applications. A further object is to provide a spring-operated automatic slider, the spring action of which is obtained directly from the lock member or locking tooth itself.

To the accomplishment of the foregoing and such other objects as will hereinafter appear, my invention consists in the locking slider elements and their relation one to the other, as hereinafter are more particularly described in the specification and sought to be defined in the claims. The specification is accompanied by drawings in which:

Fig. 1 is a section through a locking slider embodying features of my invention;

Fig. 2 is a front elevation of the slider;

Fig. 3 is a longitudinal section taken in the plane of the line 3—3 of Fig. 2;

Fig. 4 is a section similar to Fig. 1, but showing the slider in unlocked condition;

Fig. 5 is a longitudinal section similar to Fig. 3, but showing the slider in unlocked condition;

Fig. 6 is a section through a modified slider intended for use on an upright rather than inverted slide fastener;

Fig. 7 is a longitudinal section through the slider taken in the plane of the line 7—7 of Fig. 6;

Fig. 8 is a rear elevation of the same, drawn to smaller scale;

Fig. 9 is a section through still another modified form of slider;

Fig. 10 is a longitudinal section taken in the plane of the line 10—10 of Fig. 9;

Fig. 11 is a front elevation of the slider; and

Fig. 12 is explanatory of a detail in the construction of the slider.

Referring to the drawings, and more particularly to Fig. 1, the slide fastener may be conventional in character, it comprising tapes 12 having beaded or corded edges 14 with interlockable fastener elements 16 secured therewith. Only a fragment of the slide fastener is shown,

and it will be understood that the complete fastener may be provided with suitable top and bottom end stops. It will also be observed that the fastener is shown in inverted position, that is, it is closed by downward movement of the slider, and opened by upward movement of the slider.

The slider is generally designated 18. Referring now to Figs. 2 through 5 of the drawings, 10 the slider comprises top and bottom walls 20 and 22, these being appropriately flanged at 24 substantially in accordance with conventional practice. In the present case the top and bottom walls are formed of a single piece of metal connected by a neck 26. The neck portion or camming portion of the slider is completed by means of a generally wedge-shaped block 28 which is disposed between the walls of the slider and secured in position in any desired manner. In the 20 present case, the walls are secured to the block 28 by spot welding.

The neck portion of the slider receives a locking member 30. This is preferably a strip of spring metal extending transversely of the 25 slider through the neck portion, and having a length such that the ends of the spring strip act as locking teeth which are received between the elements of the slide fastener, as is best shown in Fig. 1. Inasmuch as the elements are staggered relative to one another on the two 30 stringers, the locking strip 30 may, if desired, be biased to accommodate this alternation of the elements, but I find that it is not necessary to do this, for the elements will oscillate or yield somewhat on one side or the other, as may be necessary to receive the locking strip, even when the strip is disposed horizontally, as shown in the drawings.

The neck portion of the slider is recessed or 40 hollowed on one side of spring strip 30, as is indicated at 32. This space is preferably obtained by bending tabs of metal 34 inwardly from the ends of neck 26. These tabs may be formed integrally with neck 26 and the main top and bottom walls of the slider. The block 28 is 45 spaced somewhat from the ends of tabs 34, thus forming the desired passage which receives the spring strip 30.

It may be pointed out that any tendency of 50 the slide fastener to open causes the elements to bear downwardly against the locking teeth. This tends to flex the center of the spring strip upwardly, which, however, is prevented by block 28. It will be observed that the corners or shoulders 55 of the slider extend far enough down-

wardly to confine the tapes and fastener elements against outward or spreading movement which might permit them to escape the ends of lock strip 30. It will also be noted in Fig. 1, that the strip is held in centered or symmetrical relation to the slide fastener, as by means of small tongues 38 struck downwardly from the center of the metal strip and engaging the ends of tabs 34.

Referring now to Fig. 4, if the lock strip 30 is bent or flexed downwardly into the recess 32, the ends or locking teeth 31 are retracted substantially into the neck portion of the slider where they will no longer interfere with movement of the slider.

The flexing of strip 30 is controlled by the finger piece or pull 40 of the slider. Referring to Figs. 2 and 3 of the drawings, the top wall 22 is provided with lugs or bails 42 which may, if desired, be struck upwardly from the body of the slider. These receive pivots 44 which may be formed integrally with pull 40. The pivots may be formed at the ends of arms 46, and the latter may be initially spread apart to facilitate attaching the pull to the slider, the arms subsequently being closed toward one another to bring the pivots 44 into the bails 42, as shown in the drawings. The pull 40 further comprises an extension or spring-actuating finger 48 which is preferably disposed between the bails 42. The top wall 22 of the slider is slotted at 47 to receive the finger 48, and block 28 is milled or otherwise cut away at 50 to clear the end of the finger. It will be evident from comparison of Figs. 3 and 5 that when the pull 40 is turned from the position shown in Fig. 3 to the position shown in Fig. 5, preparatory to moving the slider, the center of the spring strip 30 is deflected to bottom-most position, thereby withdrawing the locking teeth and permitting free movement of the slider along the stringers of the slide fastener.

The arrangement as so far described is intended for use on an inverted slide fastener. Referring now to Figs. 6 through 8, I there show a modified construction intended for use on a fastener which opens from the top downwardly. It will be seen that the slider is generally like that previously described, in comprising flanged top and bottom walls 52 and 54 connected by a neck 56, the ends 58 of which are turned inwardly to form a hollow space or recess 60. The neck portion of the slider is completed by a block 62 which may be secured in position by spot-welding the same between the walls of the slider. A spring locking strip 64 extends transversely of the slider between the block 62 and the tabs 58, and its ends function as locking teeth. As before, the strip is centered by locating tongues 66, and is prevented from flexing in the wrong direction (in this case downwardly) by the upper surface of block 62. In order to unlock the slider, the strip 64 is flexed upwardly from the solid line position to the broken line position, thereby retracting the locking teeth or the ends of strip 64.

The slider is provided with a pull 68. Inasmuch as the normal position of the pull is in a direction opposite to that maintained with the inverted slider previously described, it is necessary to somewhat change the pivoting of the pull. In the present case, the pull 68 located on the front of the slider is pivoted at the back of the slider. Specifically, the back wall 54 is provided with bails 70, and the curled end 72 of the pull

is disposed between bails 70. A pivot pin 74 is driven through the bails and the curled end 72, and is preferably received with a force fit in one of these members, for example, the curled end 72. This retains the pin 74 against axial movement without interfering with free oscillation of pull 68.

The top wall 52 of the slider is slotted at 76, and the bottom wall 54 is slotted at 78, to receive the extension or actuating finger 80 of the pull. It will be evident that when the pull is raised from the solid line position to the broken line position 68', preparatory to moving the slider, the spring strip 64 is flexed from the solid line position to the broken line position 64', the actuating finger 80 moving to the broken line position 80' and bearing against the spring strip during its movement.

If it is desired that the pull 68 move further to a position substantially perpendicular to the slider, it is merely necessary to appropriately change the location of the pivot carrying the pull. A modification of this character is shown in Figs. 9 through 12 of the drawings. Here again the slider comprises flanged top and bottom walls 82 and 84 connected by a preferably integrally formed neck 86. The latter is provided with in-turned tabs 88 forming a recess 90 into which the locking strip 92 may be flexed, as is indicated by the broken line position 92'. The lower element 94 of the neck portion is in the present case made of sheet metal instead of being a solid block. The metal is bent to V-shape, as is shown in Figs. 9 and 12. It is preferably provided with tongues 96 at the top and bottom, these tongues passing through mating holes in the walls of the slider, and being riveted to hold the member 94 in place and to prevent separation of the slider walls. The riveted ends are clearly shown in Figs. 10 and 11. The sides of member 94 are perforated at 98 to receive the pivot 100 for the pull. The walls are preferably indented around bearing holes 98, as is indicated at 101, thus providing parallel bearings, and also recessing the ends of pivot 100.

The top wall 82 of the slider is slotted at 102 to receive the extension or actuating finger 104 of pull 106. It will be evident from inspection of Fig. 10 that when pull 106 is raised from the solid line position to the broken line position 106', the actuating part 104 bears against the spring strip 92 and flexes the same upwardly to the broken line position 92'. In this way the locking action of the slider is released.

When the pull 106 is in the solid line position shown in Fig. 10, it is incapable of further downward movement. For this reason, the part 104 of the pull may itself be used to support the spring strip 92 against downward flexing. This is clearly shown in Fig. 9. A construction of this kind may also be used in the slider shown in Figs. 6 through 8, it then being unnecessary for the block 62 to support the spring strip against downward movement.

In assembling the slider of Figs. 9 through 12, the pivot portion 100 of pull 106 may first be passed through slot 102 of the slider while the walls of the slider are still spread apart in divergent relation. The pull may be turned to a position perpendicular to that shown in Fig. 11 during this operation, so that the pivot 100 will be longitudinal of the slot 102. The V-shaped piece 94 is initially made with its walls spread apart far enough to receive the pivot 100, and the walls are closed together on the pivot. The main walls

of the slider are then closed together over the tongues 96, the outer ends of which are finally riveted to hold the slider in assembled relation. Other methods of assembly may be followed, as by making the slot 102 longer than shown, and making the pull 106 narrow enough to be received through slot 102, in which case the part 94 may be assembled with the pull before the pull is added to the slider, the latter being passed through slot 102 from the inside toward the outside of the slider before the slider walls are bent together at the neck.

It is believed that the construction and operation, as well as the advantages of my improved locking slider, will be apparent from the foregoing detailed description thereof. It will also be apparent that while I have shown and described my invention in several preferred forms, many changes and modifications may be made in the structures disclosed, without departing from the spirit of the invention as sought to be defined in the following claims. In some claims reference is made to locking teeth and resilient means normally causing the same to move outwardly into locking position, and it will be understood that the ends of the spring strip are the locking teeth, while the remainder or middle portion of the spring strip constitutes the resilient means for moving the teeth. Some claims refer to a spring actuator moved by the pull, and it will be understood that the spring actuator is the finger 48 in the first form of the invention, or the parts 80 and 104, respectively, in the second and third forms of the invention, for although these parts are most simply made integral with the pull, they need not necessarily be so made, and they function as distinct parts in the complete mechanism.

I claim:

1. A locking slider for a slide fastener having interlockable fastener elements, said slider comprising top and bottom walls connected at a neck, locking teeth disposed at said neck and projecting laterally sidewardly from the inside toward the outside of the slider into the passages for the slide fastener elements, a pull pivotally mounted on said slider, resilient means located at the neck portion of the slider adjacent the teeth for normally causing said locking teeth to move in opposite direction outwardly into locking position, and means actuated by turning said pull to a position transverse of the slider for retracting the locking teeth in opposite direction into the neck of the slider.

2. A locking slider for a slide fastener including tapes having interlockable elements secured along the edges thereof, said elements having jaws clamped on the tapes and heads projecting from the jaws, said slider comprising flanged top and bottom walls connected at a neck, locking teeth disposed at said neck and projecting laterally sidewardly from the inside toward the outside of the slider into the passages for the slide fastener elements for engagement between the heads of the interlockable elements, a pull pivotally mounted on said slider, resilient means normally causing said locking teeth to move in opposite direction outwardly into locking position, and means located at the neck portion of the slider and actuated by turning said pull to a position transverse of the slider for retracting the locking teeth in opposite direction substantially within the neck of the slider.

3. A locking slider for a slide fastener having interlockable fastener elements, said slider com-

prising top and bottom walls connected by a neck portion, a spring strip extending transversely through said neck portion, a pull pivotally mounted on said slider, and a spring actuator located at the neck portion of the slider and moved by the pull, the parts being so disposed that when the pull extends in the direction of the slider an end of the spring strip projects from the neck portion to lock the slider, but when the pull is raised to a position transverse of the slider the spring strip is so flexed that the end of the strip is retracted enough to permit movement of the slider along the fastener.

4. A locking slider for a slide fastener including tapes having interlockable fastener elements secured along the edges thereof, said slider comprising flanged top and bottom walls connected by a neck portion, a spring strip extending transversely through said neck portion, a pull pivotally mounted on said slider, a passage affording movement of a part of the pull into the neck portion of the slider and against the spring strip, the parts being so disposed that when the pull extends in the direction of the slider the ends of the spring strip project from the neck portion to lock the slider, but when the pull is raised to a position transverse of the slider the spring strip is so flexed by the aforesaid part of the pull that the ends of the strip are retracted substantially within the neck portion of the slider.

5. A locking slider for a slide fastener, said slider comprising a piece of sheet metal bent to form top and bottom walls connected by an integral neck, said neck having inturned ends forming a recess at the neck of the slider, an additional camming portion secured between the walls of the slider and spaced somewhat from the inturned ends, a spring locking strip disposed transversely of the slider through the neck portion thereof, the ends of said strip projecting from the neck portion of the slider to lock the slider, a pull, a spring actuator located at the neck portion of the slider and moved by the pull, the arrangement being such that when the pull is raised the actuator bears against the locking strip and bends the same into the aforesaid recess and thereby retracts the ends of the strip enough to permit movement of the slider.

6. A locking slider for a slide fastener, said slider comprising a piece of sheet metal bent to form top and bottom walls connected by an integral neck, said neck having inturned ends forming a recess at the neck of the slider, an additional camming portion secured between the walls of the slider and spaced somewhat from the inturned ends, a spring locking strip disposed transversely of the slider through the neck portion thereof, the ends of said strip projecting from the neck portion of the slider to lock the slider, a pull, a spring actuator formed integrally with the pull, the arrangement being such that when the pull is raised the actuator bears against the locking strip and bends the same into the aforesaid recess and thereby retracts the ends of the strip enough to permit movement of the slider, and means to hold the spring strip in symmetrical relation to the slider, the parts on the side of the strip opposite the recess being such as to prevent the strip from flexing in opposite direction from the recess.

7. A locking slider for an inverted slide fastener having interlockable elements, said slider comprising top and bottom walls connected at a neck portion having a recess therein, a resilient strip of metal disposed transversely of the slider

at said neck portion, an end of said metal strip functioning as a locking tooth to lock the slider against movement, a pull pivoted on said slider and normally hanging in a direction opposite the slider for use in inverted position, a finger on said pull, said finger being so disposed that when the pull is raised to a position transverse of the slider the finger bears against the spring strip and bends the same in such a manner as to retract the end of the spring strip enough to permit movement of the slider.

8. A locking slider for an inverted slide fastener including tapes having interlockable fastener elements secured along the edges thereof, said slider comprising flanged top and bottom walls connected at a neck portion having a recess therein, a resilient strip of metal disposed transversely of the slider at said neck portion, the ends of said metal strip functioning as locking teeth to lock the slider against movement, a pull pivoted on said slider and normally hanging in a direction opposite the slider for use in inverted position, a finger on said pull, said finger being so disposed that when the pull is raised to a position transverse of the slider the finger bears against the center of the spring strip and displaces the same in such a manner as to retract the ends of the spring strip enough to permit movement of the slider, and means to prevent the spring strip from flexing in a direction opposite to that in which it is flexed by the finger on the pull when the pull is raised.

9. A locking slider for an inverted slide fastener, said slider comprising top and bottom walls connected at a neck portion having a recess therein, a resilient strip of metal disposed transversely of the slider at said neck portion, the ends of said metal strip functioning as locking teeth to lock the slider against movement, a pull pivoted on said slider and normally hanging in a direction opposite the slider for use in inverted position, a finger on said pull, said finger being so disposed that when the pull is raised to a position transverse of the slider the finger bears against the center of the spring strip and displaces the same into the recess in such a manner as to retract the ends of the spring strip enough to permit movement of the slider, and means at the spring to hold the spring in symmetrical relation to the slider.

10. A locking slider for a slide fastener including tapes having interlockable fastener elements secured along the edges thereof, said slider comprising flanged top and bottom walls connected at a neck portion having a recess therein, a resilient strip of metal disposed transversely of the slider at said neck portion, the ends of said metal strip functioning as locking teeth to lock the slider against movement, a pull pivoted on said slider and normally hanging in a direction opposite the slider for use in inverted position, a finger on said pull, said finger being so disposed that when the pull is raised to a position transverse of the slider the finger bears against the center of the spring strip and displaces the same in such a manner as to retract the ends of the spring strip enough to permit movement of the slider, means to center the spring strip against sideward displacement, and means to prevent the spring strip from flexing in a direction opposite to that in which it is flexed by the finger on the pull when the pull is raised.

11. A locking slider for a slide fastener, said slider comprising top and bottom walls connected by a neck, a spring locking strip disposed

transversely of the slider through the neck portion thereof, the ends of said strip projecting from the neck portion of the slider to lock the slider, a pull having an inwardly bent part passing through the neck adjacent the locking strip, the end of said pull being pivotally mounted on the slider at a point spaced downwardly from the top wall of the slider, the arrangement being such that when the pull is raised a part thereof near the pivot bears against the locking strip and bends the same and thereby retracts the strip enough to permit movement of the slider.

12. A locking slider for a slide fastener including tapes having interlockable fastener elements secured along the edges thereof, said slider comprising a piece of sheet metal bent to form flanged top and bottom walls connected by an integral neck, said neck having inturned ends forming a recess at the neck of the slider, an additional camming portion secured between the walls of the slider and spaced somewhat from the inturned ends, a spring locking strip disposed transversely of the slider through the neck portion thereof, the ends of said strip projecting from the neck portion of the slider to lock the slider, a pull having an inwardly bent part passing through the neck adjacent the locking strip, the end of said pull being pivotally mounted on the slider at a point spaced downwardly from the top wall of the slider, the arrangement being such that when the pull is raised a part thereof near the pivot bears against the locking strip and bends the same into the aforesaid recess and thereby retracts the ends of the strip enough to permit movement of the slider.

13. A locking slider for a slide fastener, said slider comprising a piece of sheet metal bent to form top and bottom walls connected by an integral neck, said neck having inturned ends forming a recess at the neck of the slider, an additional camming portion secured between the walls of the slider and spaced somewhat from the inturned ends, a spring locking strip disposed transversely of the slider through the neck portion thereof, the ends of said strip projecting from the neck portion of the slider to lock the slider, a pull having an inwardly bent part passing through the neck adjacent the locking strip, the end of said pull being pivotally mounted on the slider at a point spaced downwardly from the top wall of the slider, the arrangement being such that when the pull is raised a part thereof near the pivot bears against the locking strip and bends the same into the aforesaid recess and thereby retracts the ends of the strip enough to permit movement of the slider, means at the spring strip to hold the spring strip in symmetrical relation to the slider, and means on the side of the strip opposite the recess to prevent the strip from flexing in a direction opposite the recess.

14. A locking slider for a slide fastener having interlockable fastener elements, said slider comprising top and bottom walls connected by a neck portion, flanges at the sides of the slider to form slider channels, a spring strip, an end of said spring strip being disposed in one of said slider channels to normally lock the slider, fulcrum means supporting said spring strip at spaced points, a pull pivotally mounted on the slider, and a spring actuator moved by the pull, the parts being so disposed that when the pull extends in the direction of the slider the end of the spring strip projects into the slider channel to lock the slider, but when the pull is raised to

move the slider the spring actuator bears against the spring strip between the fulcrums and so flexes the spring strip in one direction that the end or locking portion of the strip is retracted from the slider channel in generally opposite direction enough to permit movement of the slider along the fastener.

15. A locking slider for a slide fastener having interlockable fastener elements, said slider comprising top and bottom walls connected by a neck portion, flanges at the sides of the slider to form slider channels, a spring strip, the ends of said spring strip being disposed in the slider channels to normally lock the slider, fulcrum means supporting said spring strip at spaced points intermediate the ends and the middle of the spring strip, a pull pivotally mounted on the slider, and a spring actuator forming a part of the pull, the parts being so disposed that when the pull extends in the direction of the slider the ends of the spring strip project into the slider channels to lock the slider, but when the pull is raised to move the slider the spring actuator bears against the spring strip between the fulcrums and so flexes the spring strip in one direction that the ends or locking portions of the strip are retracted from the slider channels in generally opposite direction enough to permit movement of the slider along the fastener.

16. A locking slider having conventional channels for a slide fastener, a lug on said slider for pivotally carrying a pull, a spring strip an end of which is disposed in one of the channels of

the slider to act as a locking tooth for engaging fastener elements and thereby locking the slider against movement, spaced fulcrums on said slider for supporting said spring strip at spaced points, 5 a pull pivoted on said lug, said pull having a portion for bearing against the spring strip between the fulcrums when the pull is raised to move the slider, the resulting flexing of the spring strip between the fulcrums in one direction causing movement of the end locking portion of the spring strip in generally opposite direction out of the slider channel with consequent unlocking of the slider.

17. A locking slider having conventional channels for a slide fastener, a lug on said slider for pivotally carrying a pull, a spring strip the ends of which are disposed in the channels of the slider to act as locking teeth for engaging fastener elements and thereby locking the slider against movement, spaced fulcrums on said slider for supporting said spring strip at spaced points intermediate the ends and the center portion of the spring strip, a pull pivoted on said lug, said pull having a portion for bearing against the 20 spring strip between the fulcrums when the pull is raised to move the slider, the resulting flexing of the spring strip between the fulcrums in one direction causing movement of the end locking portions of the spring strip in generally opposite direction out of the slider channels with consequent unlocking of the slider.

BERNARD S. FRANKLIN.
